UNITED STATES PATENT OFFICE.

EDWARD W. LINDQUIST, OF CHICAGO, ILLINOIS, ASSIGNOR TO RALPH BAGGALY, OF PITTSBURG, PENNSYLVANIA.

APPARATUS FOR FEEDING AND DISTRIBUTING MOLTEN MATERIAL IN BLAST-FURNACES.

SPECIFICATION forming part of Letters Patent No. 789,160, dated May 9, 1905.

Application filed May 20, 1904. Serial No. 208,959.

To all whom it may concern:

Be it known that I, EDWARD W. LINDQUIST, of Chicago, in the county of Cook and State of Illinois, have invented a new and useful Apparatus for Feeding and Distributing Molten Material in Blast-Furnaces, of which the following is a full, clear, and exact description, reference being had to the accompanying drawings, in which—

10 Figure 1 is a cross-section on the line I I of Fig. 2. Fig. 2 is a cross-section on the line II II of Fig. 1. Fig. 3 is an elevation of one end of the apparatus and illustrates the method of tilting the vessel and one of the 15 water-circulation pipes.

My invention has been designed primarily for the practice of the invention disclosed in an application, Serial No. 199,027, filed by Ralph Baggaley and C. M. Allen on March 20, 1904, for a method of smelting ores and cleaning converter-slags; and it constitutes one of a series of inventions for the manufacture of blister-copper, one of which inventions for an apparatus for distributing molten slag 25 in a blast-furnace was filed by Ralph Baggaley and C. M. Allen on March 31, 1904, Serial No. 200,866.

My present invention relates to a number of important features not disclosed in the application above referred to.

30 I use in my present apparatus a single centrally-located receptacle for the distribution of the molten material. I locate it just sufficiently above the level of the charging-floor so that the feeding of ores will not be obstructed and the draft of the furnace will not be interfered with.

I am enabled to use my apparatus in a furnace with an ordinary hood and stack, where- 40 as in the apparatus described in the application above referred to the top of the hood is entirely occupied by the slag-distributing troughs and in lieu of a stack a downtime must be provided at a lower level than the 45 distributing-troughs.

In the drawings, 2 is a trough-shape vessel flaring from the bottom to the top, which is used to receive the molten material and distribute it evenly in the furnace. It has end

trunnions 3 and is supported by flanges 2' 50 in a cradle composed of beams 4, which are preferably flanged beams. Water-pipes 5 are provided to maintain a cooling-water circulation through each side of the cradle and lead to the cradle through the trunnions, as 55 shown in Figs. 1 and 3. The trunnions are mounted in bearing-blocks 6, supported, preferably, by beams 7 and columns 8, and they enable the vessel to be tilted for the purpose of distributing the molten material over the 60 furnace charge or to be entirely inverted to discharge into the crucible any skull that may be left after pouring out the molten contents. The power for tilting the vessel is supplied by means of a worm-gear 9 or other 65 equivalent device. 10 is a spout through which the molten slag or matte to be distributed is introduced into the vessel 2 from a ladle 11.

My invention is intended to supply to a 70 smelting-furnace copper converter-slag which usually contains mineral values. As the distributing vessel extends over the entire length of the furnace-crucible I can by 75 tilting it distribute the slag evenly along the entire inner wall of either side of the furnace. In smelter practice as conducted prior to the inventions above cited converter-slag was allowed to cool and congeal and was then 80 broken up into pieces of suitable size at a great expense—and was fed cold to the smelter in about the same manner in which ores are fed. Such congealed slag demands proportionate consumption of carbonaceous fuel to reheat and remelt it, while in the 85 method which is practiced with great economy by use of my apparatus all this labor, fuel, time, and expense are saved by delivering the converter-slag directly into the furnace in a hot molten condition, in which it 90 not only requires no fuel to melt it, but contributes its own high heat to the contents of the furnace-crucible. I thus reduce materially the cost of smelting. An additional advantage of this method of feeding molten 95 converter-slag to a blast-furnace is that such slag is always intensely basic, and as a rule is composed principally of iron. Hence the scaf-

folds or chilled masses of highly silicious ores, &c., which are an unpleasant and expensive feature of present blast-furnace practice, are readily heated, dissolved, and dropped into the crucible when this intensely hot and corrosive basic slag is poured in molten form upon that portion of the scaffold that is wedged firmly against the interior side walls. By inverting the vessel any skull that may be left in it after a molten charge of slag has been poured will be readily discharged into the crucible of the furnace. The vessel is so placed within the furnace-hood and at or near the level of the charging-openings that it can be readily seen and its operation noted by the furnaceman. Its location within the hood is such that the cold air entering the doors from each side of the furnace will necessarily impinge directly upon the supporting-cradle, as well as upon the vessel itself, and will protect the mechanism to an important extent. The locating of this apparatus at this point in the furnace-hood not only permits the operator to observe it at all times, but also permits the pouring of the molten slag into the furnace at the lowest level possible. The entire apparatus is thus placed as near to the top of the jackets as is consistent with maintaining the room required for charging the furnace on each side. It permits the use of the entire upper part of the furnace for stack-room, yet it does not permit the escape of any of the furnace-gases other than through the hood or through the stack even when the vessel is revolved. The escape of gases into the furnace-building has been an unpleasant feature of the apparatus above referred to. The vessel is purposely constructed of even thickness in cross-section throughout its length, so that the varying temperature incident to its use will affect it uniformly and will not injure it. Its shape is such that the molten slag cannot form a bond within it calculated to obstruct the discharge of its molten contents or of the resultant skull. All parts of the mechanism are well protected from contact with the molten slag. The inlet and the outlet of the water-circulation system are especially designed to maintain the moving surfaces of the trunnions that sustain the weight of the cradle and pouring vessel at as low a temperature as possible. The movement of the trunnions in these bearings is of course insignificant; but they must be protected against the constantly-increasing heat and the gases of the furnace, so that the lubrication will not be destroyed and friction and cutting produced. While in use the long trough-shape slag vessel is very liable to become red-hot through the entrance of the hot molten slag, and as the ability of cast-iron to sustain weight is greatly reduced when it is heated, especially when it is red-hot, it is apparent that the ves-

sel when heated by the molten slag would soon become unable to sustain the heavy burden unless provision be made for this purpose. Therefore to guard against accidents I have suspended it by the flanges 2' throughout its entire length on strong wrought-metal beams, and I protect the beams against undue heating by water-pipes on each side, through which a continuous circulation of the cooling medium is maintained.

Doubtless many modifications of my invention will naturally suggest themselves to those skilled in the art, since

What I claim is—

1. Apparatus for feeding molten material in a blast-furnace, comprising a vessel extending along the furnace-crucible below the top of the hood; substantially as described. 80

2. Apparatus for feeding molten material in a blast-furnace, comprising a tilting vessel supported in bearings on the furnace structure, and a metal cradle for supporting it; substantially as described. 85

3. Apparatus for feeding molten material in a blast-furnace, comprising a tilting vessel supported in bearings on the furnace structure, a metal cradle for supporting it, and water-passages for cooling the frame and trunnions of the vessel; substantially as described. 90

4. Apparatus for feeding molten material in a blast-furnace, comprising a tilting vessel supported in bearings on the furnace structure, a metal cradle for supporting it, and mechanism for tilting the vessel; substantially as described. 95

5. Apparatus for feeding molten material in a blast-furnace, comprising a vessel extended along the furnace-crucible below the top of the hood, and a spout in the furnace-wall discharging into the vessel; substantially as described. 105

6. Apparatus for feeding molten material in a blast-furnace, comprising a vessel extending through the furnace supported by a metal cradle having trunnions, means for revolving the same, means for maintaining a circulation of cooling medium through the trunnions and along the frame, and a spout leading from the outside of the furnace to the vessel adapted to conduct the molten material thereinto from the outside of the furnace; substantially as described. 110

7. Apparatus for feeding molten material in a blast-furnace, comprising a vessel extending along the furnace, supported by a metal cradle carried on cast-metal trunnions, means for revolving it in either direction and for completely inverting it when necessary; substantially as described. 120

8. Apparatus for feeding molten material in a blast-furnace, comprising a tilting vessel supported in the furnace at the level of the charging-doors; substantially as described. 125

9. Apparatus for feeding molten material in a blast-furnace, comprising a tilting vessel supported in the furnace at the level of the charging-doors and exposed to the air-draft therefrom; substantially as described.

10. Apparatus for feeding molten material in a blast-furnace, comprising a tilting vessel supported in the furnace at the level of the

charging-doors, and means for water-cooling it; substantially as described. ¹⁰

In testimony whereof I have hereunto set my hand.

EDWARD W. LINDQUIST.
